PAGE 2

Fig.3

FIG. 4

FIG. 5

FIG. 1 is a view in perspective of a pump, showing my design;

FIG. 2 is a view similar to that of FIG. 1 but illustrating the under side thereof;

FIG. 3 is a perspective view illustrating the pump drive shaft mounting;

FIG. 4 is a perspective view of the pump illustrating the portion of the pump drive shaft mounting not shown in FIG. 3; and

FIG. 5 is a rear elevational view of the pump.

I claim:

The ornamental design for a pump, substantially as shown.
